UNITED STATES PATENT OFFICE.

WILLIAM BARTHOLOMEW AND JAMES F. BRODERICK, OF CHICAGO, ILLINOIS, ASSIGNEES TO TROY LAUNDRY MACHINERY COMPANY, LTD., OF CHICAGO, ILLINOIS, A CORPORATION OF NEW YORK.

SAFETY DEVICE FOR CENTRIFUGAL EXTRACTORS.

1,214,987.

Specification of Letters Patent.

Patented Feb. 6, 1917.

Application filed February 18, 1913. Serial No. 749,189.

To all whom it may concern:

Be it known that we, WILLIAM BARTHOLOMEW and JAMES F. BRODERICK, citizens of the United States, residing at Chicago, in the county of Cook and State of Illinois, have invented certain new and useful Improvements in Safety Devices for Centrifugal Extractors, of which the following is a specification.

10 Our invention relates in general to laundry machinery, and more particularly to centrifugal extractors.

The high speed at which the baskets of centrifugal extractors are rotated renders their use dangerous to careless operators unless such extractors are provided with safety appliances for preventing access to the baskets while they are rotating. In order that such safety devices may fully protect the operators, it is necessary that access should be prevented to the baskets not only while the power is applied to rotate them, but after the disconnection of the driving power and while the baskets continue to rotate by momentum at dangerous speeds.

The primary object of our invention is to provide a centrifugal extractor in which the cover must be locked in closed position when power is applied to rotate the basket, and in which the cover cannot be unlocked while the basket continues to rotate.

A further object of our invention is to provide a centrifugal extractor having a cover for preventing access to the revolving basket, in which power can only be applied to the basket after the cover has been locked, and in which the driving means which necessarily rotates while the basket rotates will be so connected with the cover that it cannot be opened until such driving means have ceased to move.

A further object of our invention is to provide an improved centrifugal extractor, which will be simple in construction and operation, and the use of which will be unattended by any possible injury to the operators.

Our invention will be more fully disclosed hereinafter with reference to the accompanying drawings, in which the same is

illustrated as embodied in a convenient and practical form, and in which—

Figure 1 is a side elevational view;

Fig. 2, an enlarged detail view of the cover hinge and adjacent parts;

Fig. 3, a sectional detail through the cover bolt;

Fig. 4, a plan view, portions of the basket and cover being broken away; and

Fig. 5, a rear elevational view.

Similar reference characters are used to designate similar parts in the several figures of the drawings.

Reference letter A designates the casing of a centrifugal extractor within which is inclosed the rotating basket a. B designates the support for the casing which comprises standards and a base b adapted to rest on the floor or other underlying supporting surface. C designates the cover for the casing which, when closed, overlies the basket and prevents access thereto. D designates a vertical spindle upon the upper end of which the basket is mounted and by which it is rotated. d designates a pulley concentrically surrounding and fixed to the spindle D. E designates a driving belt engaging the pulley d and guided by pulleys F' and F''. F indicates a driving pulley around which the belt E extends.

Suitable supporting means are provided for the idler pulleys and also the driving pulley which may conveniently consist of a pair of brackets G' and G² secured to the standards of the casing support B and also to the casing A, as shown in Figs. 1 and 4. Depending from the brackets G' and G² are supplemental brackets g' and g² in which are journaled the guide pulleys F' and F''. The upper ends of the pair of brackets G' and G² are provided with bearings g³ and g⁴ in which are journaled the ends of the shaft H upon which is fixed the driving pulley F.

Mounted upon the shaft H are pulleys H' and H'', the former of which is fixed to the shaft while the latter is loose thereon. h designates a power belt leading from any suitable source of power and adapted to engage either of the pulleys H' or H'' by 100

- means of a suitable belt shifter L comprising parallel curved rods l' and l^2 between which the power belt h extends. The belt shifter L is secured to a horizontally reciprocating rod K which is mounted in bearings g^5 and g^6 mounted in any suitable manner upon the extractor casing but preferably connected with the main supporting brackets G' and G^2 . M designates a lever 5 for actuating the belt shifter pivoted at m upon the bearing g^3 , and pivotally connected intermediate of its ends at k' to an arm K' secured to and projecting from the outer end of the belt shifter rod K.
- 10 The centrifugal extractor above described does not in itself constitute our present invention but is illustrated and described in order that our invention may be fully disclosed.
- 15 The cover C is provided with an extension at its rear c which forms one member of the hinge which pivotally supports the cover. The extension c is bifurcated so as to straddle a supporting bracket G which may 20 be conveniently formed as part of the main supporting brackets G' and G^2 , as shown in Fig. 5.
- 25 A bell crank lever N is pivotally mounted at n upon the bracket n' adjacent the hinge 30 of the cover, such bracket being secured to any suitable support. O designates a bolt pivotally connected by means of a slot and bolt to the bell crank lever N and adapted to be reciprocated through alined holes 35 formed in a pair of spaced ears o' and an intermediate ear o formed on the rear extension c of the cover C at a point slightly in front of the pivotal axis of the cover (see Figs. 2 and 3). Pivotally connected to the 40 lower arm of the bell crank lever N is a rod P which is pivotally connected at its other end to a detent lever R fulcrumed intermediate of its ends upon a bracket S secured to the supporting frame G^2 . The free end 45 of the detent lever R is adapted to project into the path of rotation of a series of laterally projecting lugs R' carried by the driving pulley F.
- The short crank arm U projects radially 50 from the rod u which pivotally connects the two hinge members of the cover C, such rod being fixed to rotate with the cover. U' designates a rod pivotally connected at one end to the crank arm U and at its other end extending through a guide sleeve g^7 supported by the bracket g^6 through which the inner end of the belt shifter rod K extends.
- 55 The manner of using and operation of our invention are as follows: Assuming that the cover is closed and the extractor is in operation, the parts will be in the position indicated in full lines in the drawings. The bolt O is then in engagement with the registering holes in the fixed spaced ears o' and 60 intermediate ear o on the cover C in front of

its pivotal axis. The bell crank lever N is held in position to retain the bolt O in such locked condition by means of the spring N' connected to the short arm of the bell crank lever and also to any suitable stationary support. Such position of the bell crank lever oscillates the detent lever R, through the medium of the connecting rod P, into such a position that its free end is out of the path of the lugs R' on the driving pulley F. 75 Should any attempt be made to unlock the cover by withdrawing the bolt O during the operation of the machine, such attempt would be prevented by reason of the lugs R' engaging the free end of the detent lever R 80 and preventing the same from being oscillated to the position shown in dotted lines in Fig. 5, and thereby preventing the oscillation of the bell crank lever N necessary to withdraw the bolt from locking engagement 85 with the cover. It will, therefore, be seen that the cover cannot be unlocked as long as the basket is in rotation, inasmuch as the basket rotates coincidentally with the driving pulley F through the medium of the 90 belt E.

When it is desired to open the cover, to remove the articles from which the water has been extracted and to insert other articles, it is first necessary to operate the belt shifter 95 by swinging the lever M from the position shown in full lines to that shown in dotted lines in Fig. 4, thereby shifting the belt h from the tight pulley H' to the loose pulley H^2 . The cover continues to be locked even 100 after the power has been disconnected by shifting the belt h as long as the basket continues to revolve by momentum. When the basket has come to a standstill, which is usually facilitated by the use of a brake, the 105 bell crank lever N is oscillated so as to withdraw the bolt O from locked engagement with the ear o on the cover. This movement of the bell crank lever oscillates the detent lever R so that its free end projects in the 110 path of rotation of the lugs R' , but as the pulley F on which the lugs R' are carried is not in motion, such movement of the detent lever is permitted. The cover may then be opened and such opening movement of 115 the cover projects the rod U' into the path of movement of the belt shifter rod K so that the power belt cannot be shifted to the tight pulley as long as the cover is open. When a new charge of articles have been 120 placed in the basket, the bell crank lever N is oscillated so as to withdraw the bolt O from the path of the ear o on the cover, thereby permitting the cover to be closed. The spring N' automatically oscillates the 125 bell crank lever, thereby reciprocating the bolt O into locked engagement with the ear o on the cover. The closing movement of the cover withdraws the rod U' from the path of the belt shifter rod K, thereby per- 130

mitting the power belt to be shifted to the tight pulley. The belt shifter rod K then occupies a path intercepting that of the rod U' so that the latter cannot be moved into 5 position which it must assume when the cover is open. The cover is therefore retained locked immediately upon the belt being shifted, and is further retained locked by means of the bolt O as soon as the basket 10 commences to rotate and as the lugs R' prevent the oscillation of the detent lever R in a direction to disengage the bolt O from the cover.

From the foregoing description it will be 15 observed that we have invented improved safety devices for centrifugal extractors, and similar machines, by means of which power cannot be applied to rotate the basket until the cover has been closed; in which the 20 cover cannot be opened until the driving power has been disconnected; and in which the cover will be positively locked in closed position as long as the basket continues to rotate either through the driving power or 25 by momentum after the driving power has been disconnected.

While we have illustrated and described our invention as embodied in a centrifugal extractor and have defined the same in the 30 following claims with reference to such embodiment thereof, yet we do not wish thereby to be understood as restricting the application of our invention to centrifugal extractors, but intend thereby to protect it for 35 whatever uses it may be adapted and in whatever forms it may be capable of practical embodiment.

What we claim is:

1. In a centrifugal extractor, the combination with a rotary basket, a belt for rotating said basket, a driving pulley engaging said belt, a cover for said basket, a lock for retaining said cover closed, and a movable member connected to said lock for controlling the movement thereof, said means when the cover is closed extending into the path of movement of elements carried by said driving pulley and prevented by successive contacts of said elements therewith from 50 being moved into position to disengage the bolt from the cover.

2. In a centrifugal extractor, the combination with a rotary basket, of a belt for rotating said basket, a driving pulley engaging said belt, a cover for said basket, a bolt for locking said cover in closed position, and means controlled by said driving pulley and operatively connected with said bolt for preventing the disengagement thereof from 60 the cover during the rotation of said pulley.

3. In a centrifugal extractor, the combination with a rotary basket, of a casing with 65 in which said basket is inclosed, a cover pivotally mounted on the casing, a belt for rotating said basket, a driving pulley engag-

ing said belt, a reciprocating bolt supported upon said casing and adapted to lock said cover in closed position, and means controlled by said driving pulley for preventing the disengagement of said bolt from the 70 cover during the rotation of said pulley.

4. In a centrifugal extractor, the combination with a rotary basket, of a cover for closing said basket, a belt for rotating said basket, a driving pulley engaging said belt, 75 a bolt for locking said cover closed, a bell crank lever operatively connected with said bolt, and means controlled by said driving pulley for preventing the movement of said bell crank lever to disengage said bolt from 80 the cover during the rotation of said driving pulley.

5. In a centrifugal extractor, the combination with a rotary basket, of a casing inclosing said basket, a cover pivotally mounted 85 on said casing, a bolt for locking said cover closed, a belt for rotating said basket, a driving pulley engaging said belt, a bell crank lever pivotally mounted on said casing and operatively connected to said bolt, a 90 reciprocating rod connected with said bell crank lever, and means controlled by said driving pulley for obstructing the movement of said rod and thereby preventing said bell crank lever being moved to unlock 95 the cover.

6. In a centrifugal extractor, the combination with a rotary basket, of a casing inclosing said basket, a cover pivotally mounted on said casing, a bolt for locking said cover closed, a belt for rotating said basket, a driving pulley engaging said belt, a bell crank lever pivotally mounted on said casing and operatively connected with said bolt, a reciprocating rod pivotally connected with said bell crank lever, a detent lever pivotally connected to said rod, and projections on said driving pulley having a path intersecting the path of said detent lever, thereby preventing the movement of 100 said detent lever necessary to permit said cover to be unlocked.

7. In a centrifugal extractor, the combination with a basket, of a casing inclosing said basket, a cover pivotally mounted on said casing, a reciprocating bolt supported on said casing, a projection on said cover having a hole therethrough registering with said bolt when the cover is closed, a lever for reciprocating said bolt into and out of engagement with the hole in said projection, and means for preventing the disengagement of said bolt from said projection during the rotation of the basket.

8. In a centrifugal extractor, the combination with a rotary basket, of a casing inclosing said basket, a cover hinged to said casing, a reciprocating bolt supported upon said casing, a projection on said cover having a hole therethrough registering with said 120

- bolt when the cover is closed, a bell crank lever pivotally mounted on said casing and operatively connected with said bolt, a spring connected with said bell crank lever 5 for oscillating the same to move the bolt into engagement with said projection, a belt for rotating said basket, a driving pulley engaged by said belt, a reciprocating rod connected with said bell crank lever, a detent 10 lever pivotally connected with said rod, and laterally projecting lugs on said pulley having a path intersecting the path of said detent lever, thereby preventing the moving of said detent lever necessary to permit said 15 cover to be unlocked.
9. In a centrifugal extractor, the combination with a rotary basket, of a belt for rotating said basket, a driving pulley engaging said belt, a cover for said basket, 20 means for retaining said cover in closed position, and a movable member connected with said means and having a path of movement during the opening of the cover intersecting the path of rotation of rigid parts carried

by said driving pulley, whereby the rapid 25 successive contact of said parts with said member prevents the movement thereof necessary to permit the opening of said cover.

10. In a centrifugal extractor, the combination with a rotary basket, of a belt for 30 rotating said basket, a driving pulley engaging said belt, a cover for said basket, means for retaining said cover closed, and a member connected with said means extending 35 into the path of movement of elements carried by and immovable relatively to said driving pulley when the cover is open and prevented by successive contacts of said elements therewith during the rotation of said pulley from being moved into position to 40 permit the opening of said cover.

In testimony whereof, we have subscribed our names.

WILLIAM BARTHOLOMEW.
JAMES F. BRODERICK.
